PAPER TOWEL DISPENSING MACHINE

Philip Kopf, Brooklyn, N. Y.

Application January 30, 1951, Serial No. 208,623

4 Claims. (Cl. 271—2.4)

1

This invention relates to a paper towel dispenser.

The paper towel dispenser which is herein described and claimed is the type of dispenser which is used in public washrooms in railroad terminals, meeting halls, restaurants, office buildings and the like. The paper towels are fed from a large roll of paper toweling. The paper is imperforate and it is necessary to sever predetermined lengths of the paper in order to provide the individual paper towels.

Paper dispensers of this general character are widely in use in this country, but they all suffer from one serious disadvantage: In all cases, the paper is drawn manually out of the dispenser and the dispensing mechanism merely limits the length of paper which may be drawn out at any one time. In the normal course of events, a person's hands are wet when he reaches for the paper towel to draw it out of the dispenser. Such being the case, it frequently happens that the paper tears before its full, predetermined length is pulled out of the dispenser. Besides, the exposed length of paper is apt to be contaminated by exposure to dirt and dust and to the hands of others than the user's.

It is accordingly the principal object of this invention to provide a paper towel dispenser which mechanically, and by spring action, feeds a predetermined length of paper to the person operating the same, and all that need be done after the paper is fed out of the machine is to sever it against a cutting member such as a serrated blade. The person who wishes to dispense a paper towel to himself from the machine herein claimed, in effect merely energizes the machine and the machine thereafter performs the function of feeding a predetermined length of the paper without any further manual attention. The feeding mechanism is spring powered. The person operating the dispenser simply loads a spring and the loaded spring then actuates the feeding mechanism. A predetermined length of paper is fed from the dispenser and the dispenser then locks to prevent any further feeding of the paper until the spring is once again loaded. The paper may then be severed along the serrated edge and used as desired. The paper which remains in the dispenser is supported, for all practical purposes, out of sight and out of reach and in sanitary condition until the mechanism is once again actuated and the paper is once again fed from the dispenser.

Another object of this invention is the provision of a paper towel dispenser of the character

2

described, which is so constructed as to be readily serviced, both for the purpose of renewing its supply of paper and for the purpose of maintenance. Its mechanism is virtually fool-proof, and it cannot run down since it is energized each and every time that it is used.

A further object of this invention is the provision of a suitable cabinet for the dispensing mechanism, said cabinet being provided with a lock which may be opened without a conventional type of key. The cabinet may be opened by simply pressing a pin against the latch, but since the opening to the latch is, in a sense, hidden, and since the unlocking action is so unusual and unexpected, the mechanism cannot readily be reached by vandals wishing to tamper with it.

A preferred form of this invention is shown in the accompanying drawings, in which:

Fig. 1 is a front view of a paper towel dispenser made in accordance with this invention, the front wall of its cabinet being partly broken away to expose the paper and the pressure and locking roller in engagement with the paper.

Fig. 2 is a side view looking from the left as viewed in Fig. 1, the left side wall being partly broken away to expose the roll of paper, the feeding roller and the combination pressure and locking roller engaging the paper, and the latching mechanism which locks the cabinet door, said door being shown, in dot and dash lines, in open position, and in solid lines, in closed position.

Fig. 3 is a side view of the dispensing mechanism, looking from the right as viewed in Fig. 1, said mechanism being shown in inoperative position.

Fig. 4 is a similar view showing the energizing stage, that is the step of loading the spring which actuates the feeding mechanism.

Fig. 5 is a similar view showing the spring in loaded position and the feeding mechanism ready for the feeding operation.

Fig. 6 is still another similar view showing the feeding mechanism in operation.

Fig. 7 is an opposite end view of the housing which supports the paper roll and the entire mechanism within the cabinet.

Fig. 8 is a detailed view of the spring-urged feeding arm of the feeding mechanism.

Fig. 9 is a longitudinal section through the main shaft of the paper feeding mechanism, showing the interrelationship between the operating handle and some of the major components of said feeding mechanism.

The paper towel dispenser shown in the draw-

ing is provided with a cabinet 20 which has a door 22 and it is also provided with a frame or housing 24 which carries the roll of paper 26 and the dispensing mechanism 28. The cabinet may be provided with a pair of keyhole-shaped openings 30 to accommodate a pair of screws or nails or the like for hanging the same on a wall. The shape of the cabinet is not critical but a functional shape, keyed to the shape of the structure and mechanism enclosed by said cabinet, is shown in Fig. 2. The back wall 32 in which the keyhole-shaped openings 30 are formed is a flat wall which may rest flat against the wall of the room in which the cabinet is installed. The bottom wall 34 may also be a flat wall, perpendicular to back wall 32. A slot 36 is formed in the bottom wall, parallel to the plane of the back wall, to serve as an exit opening for the paper toweling 38 which is drawn from the paper roll 26. The front wall 40 and cover or door 22 curve upwardly in a common, graceful curve leading to the top edge of the back wall of the cabinet. The curved door 22 is hinged at both ends by means of pins 42, and it is provided with at least one hinged latch 44. Latch 44 is fastened to the inside of the leading edge of the door by means of pin 46 and brackets 48 which carry said pin. A torsion spring 50 is also mounted on said pin and one end bears against the door and the other end bears against the latch to urge said latch into locking position as shown by means of solid lines in Fig. 2. Latch 44 is thereby caused to engage a flange 52 which is supported by the back wall of the cabinet and the door is thereby locked and held in closed position. To disengage the latch from flange 52, all that need be done is to insert a pin 54 into a hole 56 formed in the door and to push the latch, against the action of spring 50, out of engagement with flange 52. See the dot and dash lines in Fig. 2.

The frame or housing 24 which supports the paper roll 26 and the feeding mechanism may be placed on the floor or bottom wall 34 of the cabinet as Fig. 6 clearly shows. The roll of paper is wound around a rod 58 and slots or notches 60 and 60a are formed in the side walls 62 and 64, respectively, of said frame or housing 24 to accommodate the ends of said rod 58. The paper roll is thereby adequately supported and at the same time, it is free to rotate to feed the paper therefrom.

It will be noted in Figs. 2 and 6 that the paper, after leaving the paper roll 26, passes between a feed roller 66 and a combination pressure and locking roller 68. Torsion spring 70 bears against pressure roller 68 to press said roller against the paper and to press the paper against feed roller 66. It will be noted that roller 68 is a transversely grooved roller, having a plurality of uniformly spaced, annular grooves 69 formed thereon for a better gripping action on the paper. It will also be noted in Fig. 7 that the shaft 67 of said grooved roller rides in slots 71, instead of in holes, so as to allow said roller to move toward and away from the feed roller 66. As has above been indicated, the paper leaves the cabinet through slot 36. A serrated blade 72 is provided along said slot 36 for severing the paper into individual paper towels.

Patrons may operate the towel dispensing mechanism by means of an L-shaped crank handle 74 whose horizontal portion 75 is rotatably supported by bracket 78 of frame 24. A shaft 76 is provided which is fixed at one end to side wall 62 of said frame 24 by means of a flanged

produces no effect upon the angular position of said gear wheel. Nor could any effect be produced on the angular position of said gear wheel since it is locked against rotation by lug 106 of arm 96. Handle 14 may now be released and spring 88, acting upon arm 86, will swing both said arm and said handle back in clockwise direction to their Fig. 3 positions. Arm 86 will once again engage arm 96 and said arm 96 will thereby be caused to disengage the teeth of gear wheel 90. The gear wheel is now free to rotate under the influence of loaded spring 82, acting through arm 80 and pawl 94. The gear wheel 90 is thus caused to turn in clockwise direction and since it meshes with gear wheel 92 on roller 66, said roller is caused to rotate in counter-clockwise direction. And since roller 68 presses tightly against paper 38 and causes said paper to press tightly against roller 66, the effect is to cause roller 68 to turn in clockwise direction and the paper to be pulled downwardly from roll 26. See the arrows in Fig. 6.

There are two factors which determine the length of paper which rollers 66 and 68 feed from the machine. The first is the angular distance travelled by gear wheel 90. The second is a locking mechanism which locks roller 68 against rotation. Referring now to the angular distance travelled by gear wheel 90, it will be seen that an adjustable stop 108 is provided to limit the counter-clockwise movement of arm 80. This stop member 108 may be raised or lowered, depending upon whether the range of movement of arm 80 is to be shortened or lengthened. The range of movement of arm 80 naturally determines the distance of angular travel of gear wheel 90. It will be noted in Fig. 1 that stop member 108 is supported by means of a pin 110 in any one of three communicating slots 112 formed in the front wall of the cabinet. In Fig. 1, pin 110 is shown to occupy the middle slot but it may be moved into the upper slot to shorten the stroke of arm 80 or into the lower slot to lengthen its stroke. Slots 112 extend diagonally downwardly so as to retain pin 110 in whichever of said slots it may be placed and to prevent accidental dislodgement thereof. A handle member 114 is attached to stop member 108 so as to facilitate adjusting the position of said stop member.

The stop member which acts upon roller 68 is a hook-shaped leaf spring 116. One end of said leaf spring is fastened by means of rivets 118 to the top of arm 80 on flange 80a. The opposite end is the hook-shaped end 120 which is adapted to engage toothed wheel 122 on roller 68, when arm 80 is in its Fig. 3 position. It will be noted in Fig. 3 that when arm 80 is in its inoperative position, that is at the end of a feeding stroke, leaf spring 116 is bent over the pivoted end of said arm 80, and it is thereby shortened sufficiently for its hook end 120 to pull upwardly and to engage the teeth of toothed wheel 122. This prevents the toothed wheel from rotating and hence, it prevents roller 68 from rotating. Since the two rollers 68 and 66 are pressed toward each other on opposite sides of the paper, this locking action against toothed wheel 122 prevents further feeding of the paper from the paper roll. When, however, arm 80 is caused to move in counter-clockwise direction, spring 116 unbends itself and thereby lengthens sufficiently to disengage toothed wheel 122 as Fig. 4 clearly shows. It is at this time that arm 96 takes over and locks gear wheel 90 against rotation. But when the handle swings back to its inoperative position, and arm

86 reengages arm 96 and frees said arm 96 from gear wheel 90, the entire mechanism is free to operate since neither said arm 96 nor said spring 116 is in operative position. This may be seen in Fig. 6 where arm 80 is shown moving in clockwise direction and pushing gear wheel 90 along with it.

The foregoing is illustrative of a preferred embodiment of this invention, and it will clearly be understood that this embodiment may be modified in many respects within the broad scope and spirit of the invention.

Having thus described my invention, what I claim as new and desire to secure by Letters Patent, is:

1. A web feeding mechanism for feeding paper toweling from a roll in a towel dispensing cabinet machine, said mechanism comprising a pair of rollers rotatably mounted in said cabinet and gripping the paper web between them as it unwinds from the roll, a gear train operatively connected to one of said rollers, a pivotally mounted handle, a first arm fixedly connected to said handle, a second arm pivotally mounted adjacent said first arm and engageable therewith, a pawl on the second arm which engages and operates the gear train when the second arm pivots in clockwise direction, and a spring engaging said second arm, said handle being movable in counter-clockwise direction to push said second arm in counter-clockwise direction by means of the first arm and thereby to load the spring, said handle being movable in clockwise direction to disengage the first arm from the second arm and thereby to free the second arm for clockwise movement in response to the action of the loaded spring, whereby the pawl is caused to engage and operate the gear train and thereby to turn the roller to which said gear train is operatively connected and to draw the paper web from the paper roll, a third, pivotally mounted, spring-urged arm which is situated in the path of movement of the first arm, said third arm being normally urged by its spring in counter-clockwise direction to engage the gear train and to lock it against operation, said first arm being movable with the handle in clockwise direction to engage said third arm and to disengage said third arm from the gear train, and thereby to free the gear train for operation in response to the clockwise movement of the pawl on the spring-urged second arm.

2. A web feeding mechanism in accordance with claim 1 wherein a toothed wheel is connected to the second roller, and a toothed wheel-engaging member is connected to the second arm, said toothed wheel-engaging member comprising a relatively long, flat leaf spring which is attached at one end to said second arm and which is provided with a hook-shaped portion at its opposite end, said leaf spring being movable into abutment with the toothed wheel on the second roller when the second arm approaches the end of its clockwise travel, said leaf spring being bendable against the pivoted end of said second arm when the second arm reaches the end of its clockwise travel, to shorten the straight-line distance between the two ends of said leaf spring, and thereby to bring its hook-shaped end into engagement with said toothed wheel on the second roller and to lock said second roller against rotation.

3. A web feeding mechanism for feeding paper toweling from a roll in a towel dispensing cabinet machine, said feeding mechanism compris-

ing a first roller rotatably mounted in said cabinet, a second roller rotatably mounted in said cabinet, a spring engaging said second roller and urging it against the first roller so as to enable the two rollers to grip the paper web between them as it unwinds from the roll, a gear wheel on the first roller, a second gear wheel meshing with the first gear wheel, a shaft supporting the second gear wheel for rotation thereon and relative thereto, a handle pivotally mounted relative to said shaft, a first arm fixed to said handle, a second arm pivotally mounted on said shaft for pivotal movement into and out of engagement with the first arm, a pawl on the second arm which engages the second gear wheel and turns said second gear wheel in clockwise direction when said second arm pivots in clockwise direction, and a spring which engages said second arm, one end of said spring being fixed to the shaft, said handle being movable relative to said shaft in counter-clockwise direction to push said second arm in said direction by means of the first arm and thereby to load the spring, said handle being movable in clockwise direction to disengage the first arm from the second arm and thereby to free the second arm for clockwise movement in response to the action of the loaded spring, whereby the pawl is caused to engage the second gear wheel and to turn said second gear wheel in clockwise direction, and thereby to cause the first gear wheel and the roller on which it is mounted to turn in counter-clockwise direction and to draw the web, in cooperation with the second roller, from the paper roll, a third, pivotally mounted, spring-urged arm situated in the path of movement of the first arm, said third arm being movable in counter-clockwise direction to engage the second gear wheel and to lock it against rotation, said first arm being movable with the handle in clockwise direction to engage said third arm and to disengage said third arm from said second gear wheel, and thereby to free

said second gear wheel for rotation in response to the clockwise movement of the pawl on the spring-urged second arm.

4. A web feeding mechanism in accordance with claim 3, wherein a toothed wheel is connected to the second roller, and a toothed wheel-engaging member is connected to the second arm, said toothed wheel-engaging member comprising a relatively long, flat leaf spring which is attached at one end to said second arm, and which is provided with a hook-shaped opposite end, said leaf spring being movable into abutment with the toothed wheel when the second arm approaches the end of its clockwise travel, said leaf spring being bendable against the pivoted end of said second arm when the second arm reaches the end of its clockwise travel, to shorten the straight-line distance between the two ends of said leaf spring, and thereby to bring its hook-shaped end into engagement with said toothed wheel and to lock said second roller against rotation.
